[57] CLAIM

The ornamental design for an illuminated attachment for a motor vehicle spare tire cover, as shown and described.

DESCRIPTION

FIG. 1 is a front elevation view of an illuminated attachment for a motor vehicle spare tire cover showing my new design it being understood that the broken lines are for illustrative purposes only and form no part of the claimed design;

FIG. 2 is an enlarged top, front perspective view thereof;

FIG. 3 is an enlarged rear elevation view thereof;

FIG. 4 is an enlarged side elevation view thereof;

FIG. 5 is an enlarged top plan view thereof taken;

FIG. 6 is a front elevation view of an illuminated attachment for a motor vehicle spare tire cover showing a second embodiment of my new design wherein the sole difference resides in the downward arcuate extension of the lower portion thereof it being understood that the broken lines are for illustrative purposes only; and
FIG. 7 is a front elevation view of FIG. 6 on a reduced scale shown in association with a van which is depicted in broken lines for illustrative purposes only.

The circumferentially spaced circles within the raised tubular bead are understood to represent electrically illuminated bulbs.
